UNITED STATES PATENT OFFICE.

CHARLES S. ASH, OF BUFFALO, NEW YORK.

DESIGN FOR A HUB FOR WHEELS.

45,830.

Specification for Design.

Patented May 26, 1914.

Application filed January 9, 1914. Serial No. 811,278. Term of patent 14 years.

To all whom it may concern:

Be it known that I, CHARLES S. ASH, a citizen of the United States, residing at Buffalo, in the county of Erie and State of New York, have invented a new, original, and ornamental Design for Hubs for Wheels, of which the following is a specification.

In the accompanying drawings: Figure 1 is a side elevation of a hub for wheels showing the design. Fig. 2 is a perspective view thereof.

The characteristic features of the design consist in the particular form of the hub of thin material, as shown, having a round

body, increasing in diameter toward its ends; one end terminating in an enlarged flange, having holes in its radially extending surface, said holes being outwardly reinforced with tubular bosses, and having the other end terminating in an inwardly bent peripheral edge.

I claim:

The ornamental design for a hub for wheels as shown and described.

CHARLES S. ASH.
